UNITED STATES PATENT OFFICE.

HOMER W. JONES AND RALPH R. SMITH, OF JACKSON HEIGHTS, NEW YORK, AS
SIGNORS TO NATIONAL CARBON COMPANY, INC., A CORPORATION OF NEW YORK.

BATTERY LANTERN.

Application filed March 2, 1925. Serial No. 12,699.

This invention relates to battery lanterns. It has for its principal object to simplify and make less expensive the mounting upon the casing body of the lamp, the reflector, and the lens ring for enclosing the lamp and the reflector.

To this end the casing body, which may be of mouldable sheet metal, is died to form an annular boss or flange for supporting the lens ring and the metal lying within the flange is formed into a support for the reflector and the lamp at the rear ends thereof. The forming of the reflector and the lamp support from the metal within the flange utilizes material which would otherwise be wasted, avoids the attachment to the casing of additional lamp and reflector supporting means, reduces the number of manufacturing operations and the handling of material, and provides a sturdy organization.

Other advantages and objects will herein-after appear.

In the drawings, Fig. 1 is a front elevation of a battery lantern embodying one form of the present invention;

Fig. 2 is a sectional side elevation thereof;

Fig. 3 is a front elevation of a fragment of the casing body before the lens ring, the reflector and the lamp have been applied thereto;

Fig. 4 is a view similar to Fig. 3 of a portion of a casing embodying a different form of the invention; and

Fig. 5 is a vertical section on the line 5—5 of Fig. 4.

The battery lantern comprises a casing body 1, a removable cover 2, a bail handle 3, and a lens ring 4, that encloses a lens 5, a reflector 6 and an incandescent lamp 7. A battery comprising two dry cells 8 connected in series, furnishes current to the lamp 7.

In the form of the invention shown in Figs. 1 to 3 a portion of the front of the casing body 1 is pressed outward to form an annular flange or boss 9 for supporting the lens ring 4. The lens ring 4 fits closely upon the flange 9, being held thereto by interfitting grooves 11 and projections 12 formed on the ring and flange, respectively. The casing material within the boss is dished inwardly and cut away with the exception of a lamp and reflector supporting arm 13 formed to extend downward beyond the center of the annular flange 9. An internally threaded

sleeve 14 is mounted coaxially with the flange 9 in an opening 15 in the arm and serves both as a support for the reflector 6 and a socket for the lamp 7. The sleeve 14 forms an electrical conductor to the lamp 7 but is insulated from both the reflector 6 and the casing arm 13. The opening 15 in the supporting arm 13 and an opening in the reflector 6 are both large enough to permit the sleeve 14 to pass through them without engaging their sides. In assembling the sleeve 14 with the reflector 6 and the casing the sleeve is passed successively through an insulating washer 16, the reflector 6, a second insulating washer 17, the casing arm 13, a third insulating washer 18 and a washer 19 of conductive material such as brass. The sleeve 14 is positioned out of contact with the arm 13 and the reflector 6, and its end portion 20 is then upset to hold the assembly together. The upset portion 20 cooperates with collar 21 at the forward end of the sleeve 14 to clamp all the elements on the sleeve together against relative movement.

A conductor 22 connected to the positive battery terminal 23 and to the conductive washer 19, carries the electric current to the lamp 7. The current passes from the negative lamp terminal through a flat resilient conductor strip 24 which is carried by the casing but insulated from it. Fingers or tongues 25 punched from the casing arm 13 and bent inwardly from it hold the conductor strip 24 stationary with its lower end in position to press against the center lamp terminal.

The conductor strip 24 is supported at its upper end in position to cooperate with a switch mounted on the casing. This switch is generally similar to the one described and claimed in the application of Lee J. Voorhees, Serial No. 8,803, filed Feb. 12, 1925.

It comprises a switch lever 26, that passes through the casing and is swingable in a plane perpendicular to the casing into and out of engagement with the conductor 24. A combined bearing, guide and detent member comprising a base 27, guides 28 and detent fingers 29 cooperates with the lever 26. It is a feature of this invention, however, that the base also has a projecting arm 30 for supporting an end of the conductor 24 in cooperative relation to the switch. One or more fingers 31 formed upon the arm 30

are wrapped around but insulated from the conductor 24 to hold it in place.

Movement of the switch lever 26 into contact with the conductor 24 closes the lamp-battery circuit, joining the conductor with the negative battery terminal 32 through the casing 1 and an insulated conductor 33 that connects the casing to said terminal.

In Figs. 4 and 5 there is illustrated another embodiment of the invention. In this embodiment a casing 34 is formed to provide a lens ring supporting boss 35, and a reflector and lamp support 36 is formed within the boss without cutting any of the casing material away. This form of invention is otherwise the same as the one already described. A hole 37 is provided centrally of the support for the reception of a lamp and reflector holding sleeve, and fingers 38, similar to fingers 25, are punched from the support for securing a conductor in position to contact the center lamp terminal.

Variations may be resorted to within the scope of the invention and parts of the improvements may be used without others.

We claim:

1. In a battery lantern, the combination with a lamp and battery in circuit therewith, of a casing body enclosing the battery, said body having a flange formed on its front face, a lens ring supported on said flange, a reflector, and means formed from the casing body material extending rearwardly of said reflector for supporting the reflector and the lamp within the lens ring.

2. In a battery lantern, the combination with a lamp and a battery in circuit therewith, of a casing body of sheet material enclosing the battery, said casing having a circular lens ring supporting flange formed on the front thereof, and a lamp supporting arm extending inward from the flange, means electrically connecting the lamp and battery comprising a conductor positioned to press against a terminal of the lamp when the lamp is inserted in operative position, and means on the lamp supporting arm in proximity to the lamp for securing the conductor in said position.

3. In a battery lantern, the combination with a lamp and a battery in circuit therewith, of a casing enclosing said battery, said casing having a circular lens ring supporting flange formed on the front thereof and an integral lamp supporting arm within said flange, a switch operable to close and open

the lamp-battery circuit, a resilient conductor extending from the lamp to the switch and having portions located for engagement by the lamp and by the switch, and means on the lamp support for holding said conductor in position to be engaged by the lamp.

4. A battery-operated lantern, comprising the combination of a casing having an outwardly projecting flange formed from its front wall and at least a portion of such wall within said flange dished inwardly and provided with an aperture, lamp supporting means in said aperture, a lens, and a lens holding means supported by said flange.

5. A battery-operated hand lantern according to claim 4, in which said aperture is coaxial with said flange, and said lens-holding means comprises a ring detachably coupled to said flange.

6. A battery hand lantern comprising the combination of a casing having an outwardly projecting flange formed from its front wall and at least a portion of such wall within said flange dished inwardly and provided with an aperture, lamp supporting means secured in said aperture, an incandescent lamp in said supporting means, and a conductor secured to said dished wall portion and engageable by a contact of said lamp.

7. A battery-operated hand lantern according to claim 6, in which said dished wall portion has inwardly extending tongues securing said conductor to the inner side thereof.

8. A battery hand lantern according to claim 6, in combination with a battery, a switch for controlling the battery-lamp circuit, and means supporting a part of said conductor in position for cooperation with said switch.

9. In a battery lantern, the combination with a lamp, a reflector, and a battery in circuit with the lamp, of a casing body enclosing the battery, said body having a flange formed on its front face, a lens ring supported on said flange, and a lamp and reflector support formed from the casing body material inside the flange, supporting the reflector coaxially with the flange and supporting the lamp in the axis of the reflector.

In testimony whereof, we affix our signatures:

HOMER W. JONES.
RALPH R. SMITH.
